TABLE TOP AND THE LIKE

William P. De Saussure, Jr., Englewood, N. J., assignor to William P. De Saussure, Jr., and James P. De Saussure, copartners doing business as De Saussure Equipment Company, West New York, N. J.

Application September 22, 1937, Serial No. 165,009

3 Claims. (Cl. 311—108)

This invention relates to panels, such as table tops and trays, and more particularly to panels, and especially table tops, having a body plate, or core, covered with surfacing sheet material, such as a thin plate or sheet of "Bakelite" or linoleum or piece of woven or felted fabric.

The invention aims to provide an improved table top or other panel having an edge finishing strip of metal or other suitable hard material forming a frame about the edge of the body plate which serves to protect the edge of the panel against wear and other damage and to add strength to the panel and provide a pleasing finish, and also to hold firmly and securely in position surfacing sheet material applied to the body plate, and which, further, is readily removable and replaceable, making it possible to renew the surface covering at relatively small cost.

To these ends the invention comprises a panel having a body plate, a covering of sheet material, and an edge frame formed of one or more pieces of strip material, most desirably a suitable metal, which has a flange extending inwardly over the margin of the cover sheet and which is secured to the body plate by clamping members engaging the under side of the body plate and the frame strip and serving to clamp the flange of the frame against the cover sheet. The invention includes various additional features. An understanding of the invention can best be given by a detailed description in connection with drawing, and such a description will now be given in connection with the accompanying drawing illustrating a table top embodying the various features of the invention in the form now considered best.

In said drawing:

Fig. 1 is a sectional view of the table top taken on line 1—1 of Fig. 2;

Fig. 2 is a bottom plan view of the table top;

Fig. 3 is a perspective view on a larger scale of a part of the body plate and covering sheet and edge frame and illustrating the way in which the abutting ends of the frame strip are locked together;

Fig. 4 is a section taken on line 4—4 of Fig. 3; and

Fig. 5 is a view similar to Fig. 4, but showing a covering sheet of flexible woven fabric.

Referring to the drawing, and first to Figs. 1 to 4, the table top illustrated comprises a body plate 10 which may be of any suitable material, but which is most desirably made of ply wood. The upper surface of the body plate is covered with a thin plate, or sheet, 11 of surfacing material such as "Bakelite" or linoleum. Extending about the

edge of the body plate and surfacing sheet 11, is a frame 15 formed of suitable strip material, most desirably a suitable metal, such as an aluminum alloy, having along its upper edge an inwardly extending flange 16 which extends over the margin of the surfacing plate 11. The frame strip 15 is of a width greater than the thickness of the body plate and surfacing sheet, and is formed with a longitudinally extending hole or bore 17 which for convenience in production extends throughout the length of the strip and the vertical dimension of which is most desirably substantially greater than its horizontal width, and from which a slot 18 opens through the inner vertical wall or surface of the strip. The distance from the under side of the flange 16 to the lower edge of the slot 18 is slightly greater than the combined thickness of the body plate 10 and covering sheet 11 at the edges thereof, and the bore 17 extends downward somewhat below the lower edge of the slot.

The bore 17 serves two purposes. It provides holes in the ends of the frame strip to receive a locking bar, and it serves in place of separate recesses to receive the ends of clamping members by which the edge frame is releasably secured with the straight portions thereof held against the edge of the body plate and with its top flange held tightly against the margin of the cover sheet, the bore providing in effect angular recesses at desired points along the length of the strip.

The edge frame 15 may be made from one or more pieces of the strip material, the ends of which are connected to form a continuous edge molding when the frame is mounted on the body plate. As shown, the frame is formed from a single piece of the strip material bent to fit about the edge of the body plate with its ends abutting at the line 19. The abutting strip ends are secured together by a flat metal connecting bar 20 which extends into and is locked within the longitudinal holes provided by the bore 17. The connecting bar has a recess 21 near each end, and into each of these recesses a part of the wall of the bore 17 on one side of the slot 18 is upset. The abutting ends of the frame strip are thus securely locked together and the appearance of the table edge is not marred by the invisible locking means.

The edge frame is secured by a suitable number of clamping members 25 one end of each of which enters the slot 18 and hooks over the lower edge of the slot, and the other end of which is screwed or otherwise releasably secured to the

under side of the body plate. The clamping members are most desirable and as shown formed of short pieces of flat metal strip bent to provide a narrow flange at one end to serve as a hook and having a screw hole at the other end. In securing the positioned frame to the body plate, the flanged ends of the clamping plates are inserted beneath the edge of the body plate into the slot 18 of the frame, and then the plates, fulcrumed against the edge of the body plate, are turned to bring their other ends against the body plate and are secured by the screws. The clamping plates hold the straight portions of the strip tight against the edge of the body plate, and, the distance from the under side of the flange 16 to the lower edge of the slot 18 being, as stated, only slightly greater than the combined thickness of the body plate 10 and covering sheet 11 at the edges thereof, the flange 18 is drawn down to clamp the margin of the covering sheet to the body plate.

The number of clamping plates required for securing the frame and holding the covering sheet firmly against the body plate will depend on the size of the table top or other panel and the rigidity of the frame strip. For a very small panel, four clamping plates, one on each side, as shown, may be sufficient, but usually more should be used. If, as in a round or oval table top, there are no portions of the frame strip which need to be held in against the edge of the body plate, the clamping plates need not have hook ends.

The frame strip may be, and most desirably is, made by extruding a suitable metal, such as a suitable aluminum alloy, through a die. The required length of the extruded strip, in a single piece or in two or more pieces, is bent to fit the edge of the body plate, and the abutting ends are secured together as stated.

If the covering sheet is of very flexible material, such as a woven or felted fabric, a sheet of somewhat greater dimensions in all directions than the body plate is most desirably used, the marginal portions of the sheet being turned down about the edges of the body plate and then inward and secured to the under side of the body plate, as by means of a tape 30 and tacks 31 as illustrated in Fig. 5. In such case the flange 16 of the frame strip is not depended on for holding the covering sheet, but it does serve to press the sheet against the top marginal portions of the body plate, giving a very desirable and pleasing appearance.

The edge frame protects the edge and adds to the strength of the table top, and provides a decorative finish. Also, as will be seen, the edge

frame is readily removable and replaceable, permitting easy removal and replacement of the covering sheet.

What is claimed is:

1. A table top or the like, comprising a body plate, a covering of sheet material, a frame formed of strip material shaped to fit about the edge of the body plate and having a flange extending inwardly over the margin of the covering sheet, and a plurality of clamping members having hook ends, the hook end of each clamping member being hooked into an angular recess in the frame strip and the member being fulcrumed against the under edge of the body plate and its inwardly extending end being drawn toward and secured to the under side of the body plate to secure the frame strip to the body plate and to force it downward to cause its inwardly extending flange to clamp the margin of the covering sheet against the body plate.

2. A table top or the like, comprising a body plate, a frame formed of strip material shaped to fit about the edge of the body plate and having an inwardly extending top flange, and a plurality of clamping members having hook ends, the hook end of each clamping member being hooked into an angular recess in the frame strip and the member being fulcrumed against the under edge of the body plate and its inwardly extending end being drawn toward and secured to the under side of the body plate to secure the frame strip to the body plate and to force it downward to seat its inwardly extending flange.

3. A table top or the like, comprising a body plate, a covering of sheet material, a frame shaped to fit about the edge of the body plate having a hole extending longitudinally therethrough and including a slot opening through the inner side of the frame and having a flange extending inwardly over the margin of the covering sheet, and clamping members fulcrumed against the under edge of the body plate with their outer ends bearing downward against the lower edge of the slot in the frame and their inwardly extending ends drawn toward and secured to the under side of the body plate thereby to secure the frame to the body plate and to force it downward to cause its inwardly extending flange to clamp the margin of the covering sheet against the body plate, the frame being formed of one or more pieces of strip material bent to the shape of the body plate and having abutting ends thereof secured together by a connecting bar extending into and locked in the longitudinal holes in said abutting ends.
